UNITED STATES PATENT OFFICE.

LOUIS S. STROOCK, OF NEW YORK, N. Y.

LAP-ROBE.

No. 811,337.

Specification of Letters Patent.

Patented Jan. 30, 1906.

Application filed March 23, 1905. Serial No. 251,681.

To all whom it may concern:

Be it known that I, LOUIS S. STROOCK, a citizen of the United States, and a resident of the city of New York, borough of Manhattan, 5 in the county and State of New York, have invented a new and Improved Lap-Robe, of which the following is a full, clear, and exact description.

My invention relates to an improvement in 10 lap-robés, and while capable of general use in articles of this character it is especially designed for application to robes to be used in carriages and other vehicles.

The principal objects of the invention are 15 to provide means whereby the hands of the user may be protected from the cold without making any opening through the robe through which air can penetrate.

A further object of the invention is to provide 20 a receptacle for the hands, so placed in the robe as to permit the user to insert the hands and at the same time use his hands to aid in keeping the robe in proper position, this being accomplished with such a construction 25 that the robe is held close to the body and no passages provided between the robe and the body for the arms.

Further objects of the invention will appear 30 in the course of the subjoined description.

Reference is to be had to the accompanying 35 drawings, forming a part of this specification, in which similar characters of reference indicate corresponding parts in all the figures.

Figure 1 is a front elevation of a portion of a robe with one form of my invention applied thereto. Figs. 2 and 3 are sectional views on the lines 2 2 and 3 3, respectively, of Fig. 1, on 40 an enlarged scale. Fig. 4 is a front elevation of a robe provided with another form of my invention, and Fig. 5 is a sectional view of the same.

The robe is constructed with an outer or 45 front piece *a*, as usual, and with a lining *b*. In the form shown in the first three figures the front piece is provided with a pair of openings or slits *c*. These slits are preferably formed longitudinally of the robe, near 50 the upper end thereof, and there may be as many pairs of them as may be desired. Preferably there would be either one or two pairs in an ordinary robe. The front piece is provided with flaps *d*, secured to it and extending 55 outwardly in opposite directions from a point immediately above the slits, so as to

cover the latter and protect them. The lining is continuous all over the back of the robe and is not affected by the construction described above. It will be seen that by the provision of these slits the hands can be inserted through them between the upper portion *a'* thereof and the lining *b*. The space between these two portions is covered by a second lining *e*, and this lining preferably extends to the outer ends of the flaps. The lining is closed at its upper and lower sides on lines extending from the top and bottom of one slit to the top and bottom of the other, respectively. The lining *e*, together with the portion *a'* of the robe and the main lining *b*, constitutes a muff for the reception of the hands of the wearer. This muff is preferably provided with elastics *f* just inside the slits for normally closing the ends, and the lining *e* closes the space between the slits *c*, so that no air can enter between it and the main lining *b*.

In the form shown in Figs. 4 and 5 the front piece *a* is continuous, like the lining *b*, 80 and is not provided with slits; but instead a cover, preferably comprising a piece of fabric, fur, or the like *g*, is secured to the outside of the front piece along lines *h h* and has openings *k* near its ends. Beyond these openings 85 flaps *l* extend in opposite directions, and these flaps protect the openings from the air. In either form the openings provided for the hands are located vertically at or near the top of the robe, and the material of the robe 90 itself is interposed between the muff and the body of the wearer, so that no air can be conducted through the openings, and the body is protected as well as would be the case if an ordinary robe were employed, while the 95 hands also are protected. In the second form shown the fabric *g* is, if desired, provided with a lining *m*.

Having thus described my invention, I claim as new and desire to secure by Letters 100 Patent—

1. A lap-robe comprising a front piece, a lining, a cover, the robe being provided with a plurality of longitudinal openings parallel with each other, the cover on the outside of the robe extending from one of said openings to the other, and a plurality of flaps integrally connected with said cover and secured to the robe one over each opening, the robe having a passage between the openings constituting a muff, said passage being closed on lines extending from the top of one opening 110

to the top of the next and from the bottom of one opening to the bottom of the next.

2. A lap-robe comprising a front piece, a lining and a cover, said robe being provided with a plurality of longitudinal openings and a plurality of flaps connected with said cover, one projecting over each opening, the robe having a passage between the openings constituting a muff, and the front piece constituting the rear wall of said passage.

3. A lap-robe having a piece of fabric secured to the front thereof along lines at the

upper and lower edges of said piece of fabric, and provided with openings near the ends of said piece and with flaps integral with the piece of fabric and covering the openings. 15

In testimony whereof I have signed my name to this specification in the presence of two subscribing witnesses.

LOUIS S. STROOCK.
